UNITED STATES PATENT OFFICE.

WILLIAM D. GHERKY, OF PHILADELPHIA, PENNSYLVANIA.

PROPELLION MECHANISM FOR RAIL-GRINDERS.

1,095,995.

Specification of Letters Patent.

Patented May 5, 1914.

Original application filed November 9, 1911, Serial No. 659,456. Divided and this application filed September 24, 1912, Serial No. 722,134. Renewed April 2, 1914. Serial No. 829,137.

To all whom it may concern:

Be it known that I, WILLIAM D. GHERKY, a citizen of the United States, residing at Philadelphia, in the county of Philadelphia and State of Pennsylvania, have invented 5 certain new and useful Improvements in Propulsion Mechanism for Rail-Grinders, of which the following is a specification, reference being had therein to the accompanying drawing.

My invention relates to propulsion mechanism for trucks adapted to be operated on railway tracks, and the invention is especially applicable to the truck of a grinding machine such as is illustrated in my co-pending application Serial No. 659,456, filed November 9, 1911, of which application this application is a division.

An object sought to be attained is the provision of a positive and uniform propulsion of the truck in such a manner as to effect a movement of the truck either forwardly or rearwardly at the will of the operator and with all requisite convenience.

A specific feature of my invention of greatest importance is the provision of means adapted for selecting the direction of rotation imparted to the traction wheels of the truck which means is conveniently operated by operators at either side of the platform of the truck. Through this means, control of the grinding operation of the machine in which the truck is embodied through the forward and reverse movement 35 of the truck can be had as conveniently when the grinding operation is being performed on one side of the track as it can be when the grinding operation is being performed on the other side of the track.

My invention possesses other features of importance, all of which will be fully apparent in the following detailed description and each of which will be particularly pointed out in the appended claims.

My invention is illustrated in the accompanying drawings; in which—

Figure 1, which for convenience is divided into two parts, *a*—*b*, is a plan view of my improved machine. Fig. 2, also divided into two parts, *a*—*b*, is an end elevation of the machine. Fig. 2^e is a side elevation of the bottom-most portion of an auxiliary wheel showing a chock attached. Fig. 3, also divided into two parts, *a*—*b*, is a side elevation of the machine. Fig. 4 is a side view on a reduced scale of the top of the

machine and the trolley pole rigging thereon. Fig. 4^a is a transverse section of the trolley pole showing its mounting and the attachment of the adjusting handle. Fig. 5 is a sectional view of a form of spring box useful in suspending the machine during transportation. Fig. 6 shows the machine rigged for transportation, all detail being omitted.

The machine illustrated is assembled and mounted upon a horizontal truck frame composed of channel irons, 1, 2, 3 and 4, riveted and tied together at the corners by angles and gusset-plates, and cross-braced by channel irons 5 and 6, which not only serve to stiffen the main frame, but also to carry the motor 9 and its connected parts. This machine being intended for use on electric roads, an electric motor is employed, the detailed construction of which forms no part of the present invention, but which drives a shaft 10, provided with suitable outboard bearings and driving a suitable train of reducing gears shown for simplicity as 75 a worm 11, meshing with a worm-gear 12, which is fixed upon a driving shaft 13, from which power is taken to propel the machine on the tracks, and to feed the cutting or grinding wheels to be presently described. 80 On its opposite ends the motor shaft 10 carries belt-pulleys 14, 15, from which power is directly communicated to similar pulleys 16, 17, on the grinding wheel spindles. As will presently appear, the grinding 85 wheels are capable of lateral adjustment on the frame to accommodate tracks of different gages, and to permit this adjustment without interfering with the drive, the belt-pulleys, 14, 15, on the motor shaft are given 90 endwise adjustment, as indicated in dotted lines.

The machine is supported upon the track rails by a pair of track wheels, 18, 19, and a pair of travelers, 20, 21. The track wheels 100 are splined or otherwise secured for longitudinal adjustment on an axle, 22, having end-bearings, 23, 24, on the frame. The travelers, 20, 21, are secured directly beneath the ends of the cradles which carry the grinding 105 wheels, and are laterally adjustable therewith, so that all adjustments for gage are parallel and can be made accurately without any danger of throwing the parts out of line.

The grinding wheel drive is always in the same direction, but in order to run the machine back and forth over the section of the

rails to be ground, a reversible drive is required for the track wheels and their axle, and this is provided in the following manner: The driving shaft, 13, carries a pinion, 25, which meshes with a gear-wheel, 26, on a short shaft, 27. This shaft carries a pinion 28, which meshes with a gear-wheel, 29, on a shaft, 30. The shaft, 30, carries a miter-gear 31, which meshes with companion miter-gears 32 and 33, traveling loosely in opposite directions upon the axle 22, and adapted to be coupled thereto alternately by means of a sliding clutch 34, controlled by a fork 35 on a swinging lever 36 pivoted 10 at 37 to the frame member 4. With this arrangement, by swinging the lever 36, in one direction, the gear 32 will be coupled to the axle, and the machine will be slowly driven along the track through any desired distance. By then reversing the throw of the lever 36, the gear 32 is disengaged, and the gear 33 coupled to the axle, so as to reverse the motion of the machine by driving the track wheels, 18, 19, in the opposite direction. This reversal is made automatically, by means which are adjustable to permit any desired travel or amplitude of oscillation of the machine as a whole. These means are as follows: A sliding bar 38 has a central slot 39 through which the lever 36 passes. It also has at one end a slot 40, receiving a pin 41 on the lower arm 42 of a bell-crank lever, whose upper arm 43 has its end 44 projecting through a slot 45 in the lever 46 pivoted at 47 to the frame, and oscillated up and down by means of an adjustable wristpin connection 48 on a rocker-arm 49 secured upon a short shaft 50, which also carries a toothed segment 51 secured to a hub 52 and driven by a pinion 53 on one end of a shaft 54, which carries on its other end a gear-wheel 55 meshing with a pinion 56 fixed on a loose sleeve 57 adapted to be coupled to the axle 22 by means of a clutch 58 having its sliding member 59 splined on the axle, and worked back and forth by means of a fork 60 on one arm of a bell-crank lever 61, the other arm of which is connected by means of a link 62 with a rocker-arm 63 on a shaft 64 extending clear across the frame, and having at opposite sides thereof vertical hand-levers 65, so that the clutch 58 can be thrown in or out of engagement by hand from either side of the machine. The operation of this part of the machine is as follows: Power being communicated to the axle 22 in one direction or the other through one of the miter-gears 32, 33, is thereby communicated, when the clutch 58 is closed, to the pinion 56, and thence to the intermeshing gear-wheel 55 and its shaft 54. The pinion 53 is thus turned very slowly, and turns the segment 51 up or down according to the direction of its rotation. As the segment 65 moves, it rocks the shaft 50 and thereby the

arm 49, which moves the pivoted lever 46 which in turn rocks the bell-crank 43, and after a certain amount of travel of the pin 41 on the arm 42 in the slot 40 (Fig. 2), the sliding bar 38 is moved to shift the clutch-lever 36 so as to disengage the clutch and start it to reverse. To make this reversal certain, and also to permit intermediate travel of the parts between reversals, I provide a weighted lever 66 pivoted on the frame 75 at 67 at its lower end, and also pivoted to the bar 38 at 68 without lost motion. The weight on the lever is indicated at 69, and these parts are best shown in Fig. 2. When the pin 41 on the bell-crank 42 reaches the 80 end of the slot 40 in either direction, it pushes the bar 38, and with it the weighted lever 66 until the latter goes past center, whereupon the weight 69, in falling, will carry the lever 66 to the end of its stroke, 85 pulling with it the bar 38, and completing the movement of the clutch parts 36, 33 and 34. The parts thus described are all so related that when the segment 51 is in its intermediate position, with its middle tooth engaging the middle tooth on that side of the pinion 53, the machine is started and will move equal distances in both directions from the point in which it then stands, before reversing. A very simple adjustment serves 90 to determine what this distance will be. It has been stated that the pivoted lever 46 is swung up and down on its pivot 47 by the wristpin 48 on the rocker-arm 49, and as the 95 lever and rocker-arm swing on intersecting arcs, the wristpin works in a slot, shown in dotted lines at 70, in Fig. 3, and indicated also in dotted lines in Fig. 1. To vary the time, which is the same as saying the distance, of travel before reversal, it is only necessary to vary the amplitude of oscillation of the wristpin 48, since the time of oscillation of the rocker-arm is fixed. Hence 100 this wristpin is made longitudinally adjustable in the rocker-arm, as indicated in dotted lines in Fig. 1, where the pin is shown mounted on a sliding block 48^a, working radially in a slot 49^a in the rocker-arm, and reciprocated therein at will by means of a 105 screw 49^b, carrying a hand wheel 49^c. It is not to be supposed that this arrangement is unchangeable, but on the contrary it is subject to alteration and substitution, since any 110 means may be employed for this purpose which will give adjustment of the wristpin 115 and variation of the time of throw of the lever 46. 120

The hand levers 65, controlling the clutch, 58, enable the segment to be set at its middle 125 point, and then uncoupled, whereupon the machine can be driven free to the spot where it is to be started, the clutch 58 again thrown in, and automatic travel of the machine back and forth will at once begin. There is 130

still another feature, however, of great importance, which remains to be described, viz., means for independently supporting the machine and removing it from and replacing it upon the track. This means comprises a hoist, a pair of road wheels, and a power drive which can first be applied to the hoist and then to the road wheels, rendering it possible by small power to handle the entire machine, remove and replace it, which so far as I am aware has never before been accomplished.

Rising from opposite sides of the frame are posts formed of channels 7-7^a and 8-8^a. (These and the connected mechanism are best shown in Figs. 2 and 3). The posts are connected by a bridge member 120, riveted and tied to them by means of gusset plates. Each post is likewise provided with opposite diagonal braces, as 7^b, 7^c, suitably riveted at both ends to the posts and to the frames. As will be shown, the posts and their braces serve as means for suspending the entire machine in stable equilibrium when hoisted from the track.

Extending from side to side of the frame, overlying the same, and passing through the open spaces left between the members of each post, is a steel axle 121 upon one end of which the hub of the road wheel 122 is keyed, and upon the other end of which the hub 123 of the road wheel 124 can be clamped at will by means of the lock-nut 125, carrying a hand wheel 126 and exerting pressure on the cone-faced clutch 127, which, however, may be provided with clutch teeth, if desired. A nut 128 is pinned upon the outer end of the axle to prevent the hand-wheel from being accidentally backed off. An inner cone-bearing is provided for the hub 123, in the collar 129 pinned to the axle.

Sliding up and down between the post-members 8, 8^a, is a square box 130, through which the axle passes but in which it is free to rotate. Sliding between the post members 7, 7^a, is a similar square box 131, through the lower portion of which the axle passes and in which it is free to rotate. Both boxes have flanges sliding on both faces of the guides. Journaled in these boxes are sleeves 132 and 133, connected by a metal tube 134 secured to them both so that they will turn together. The axle is free to turn within these connected parts, except as hereinafter stated. The sleeves 132 and 133 serve as connected windlasses, turned by means of a power crank 135, in a manner to be described. Around the sleeve or windlass 132 is taken one turn or more of a chain 136, which is fastened to the sleeve at 137, has its upper end fastened to an eyebolt with a long stem passed through a projecting ear 138 on the bridge 120, and its lower end secured to an eyebolt with a similar long stem

passing through a bracket riveted at 139 to the frame member 7. Similarly, the sleeve or windlass 133 has around it one turn or more of a chain 140, pinned at 141, anchored at its upper end to an eyebolt with a long stem passing through a projecting ear 142 on the bridge 20, and its lower end to an eyebolt with a similar long stem passing through a bracket riveted at 143 to the frame member 8. Since the boxes, the windlass, and all connected parts, are free to slide up and down with respect to the frame, it is obvious that by turning the windlass in one direction, the chain will be wound up on the windlass to lift the machine clear of the track, and by turning the windlass in the other direction, the machine will first be lowered by unwinding the chain, and then the upper portion of the chain will be wound down around the windlass to lift the latter, together with the axle, boxes, wheels 122 and 124, and all connected parts until the wheels are clear of the ground so as to offer no obstruction to the travel of the machine back and forth on the track rails.

The sleeve 132 in practice has such a circumference that it will make only one revolution between the extreme positions of wheels hoisted on the frame, and frame hoisted on the wheels. Since the eyebolts 95 and top and bottom ends of the chains have long stems, adjustment is possible to vary the ratio between the two hoists. Thus for example, the sleeve has a circumference of approximately 12 inches. With equal division the machine will be hoisted 6 inches for transporting, and the wheels will be hoisted 6 inches for grinding; but by adjusting these eyebolts, by means of their nuts, any division of the 12 inches may be made. For example, the machine may be hoisted 9 inches for transporting, and the large wheels hoisted 3 inches for grinding. It will be remembered that the neutral point is fixed between the two hoists, because the chains 136 and 140 are pinned to the windlass or sleeve 132 at the points 137 and 141 respectively.

It will be quite obvious to those skilled in the art after reading the foregoing description of the chain hoist, that a great variety of other mechanical elements might be substituted for the chains and produce the same results. For example, a rack secured to the frame on each side, and a pair of pinions, one on each end of the windlass or sleeve 132, to coöperate with the said racks, would perform exactly the same functions, and in such case detent pawls could be provided engaging each rack or each pinion in opposite directions, to serve as stops and to lock the machine in either extreme position. A single reversible pawl might be made to act upon each rack or each pinion. As another example, a pair of cams might be employed

normally in neutral position, and when turned downward acting upon abutments on the frame to lift the large wheels and axles, but when turned upward, working against other abutments on the frame to lift the machine. Such cams would be approximately heart-shaped and secured to the axle at the upper or broad part of the heart. I consider this feature of the double hoist, and the principle involved of direct and reverse action up and down, as embodied in the different elements mentioned, to be novel and original with me and shall claim the same accordingly.

15 The mechanism for turning the windlass comprises a pinion 144, fixed on the crank-shaft 145, which is journaled in bearings 146 and 147 carried rigidly on the hub 123 of the wheel 124; a gear-wheel 148 meshing with the pinion 144, is secured to a drum 149, in which there is a notch 151, as best shown in Fig. 2. To engage with this notch a pivoted detent or dog 152 is provided, and the notch is so positioned that it will be engaged by the detent when the machine is hoisted on the wheels 122 and 124, and also when the windlass and connected parts are hoisted on the machine. When the windlass is in neutral position, that is to say with both wagon wheels and track wheels on a level as shown in the drawings, this notch is diametrically opposite the point of the detent or dog 152. A half revolution in one direction will then lift the wagon wheels 20 and hold them by the dog and notch, while a half revolution in the opposite direction will lift the machine and hold it by the same dog in the same notch. Secured to the windlass sleeve, 141, outside of the box 131, is a friction disk 153, and outside of this disk is a wheel 154, having on its periphery ratchet teeth engaged by a pawl 155 pivoted on the box 131, as is also the detent 152. The ratchet wheel 154 is locked between the 25 drum 149, and the disk 153, by friction due to the engagement of the screw-clutch 156, which in itself forms no part of the present invention, but is an important element in the combination employed. In the drawing, 30 I have shown the crank 135 provided with an extensible portion 135^a, pivoted so it can be swung in either direction, to make the crank long for working the windlass, and to make it short for turning the wheels 122 and 124. It should be noted here that the pawl 155 is never lifted.

35 The operation of these parts is as follows: Assuming that the machine is resting on the rails, and it is desired to move it, the wheels 122 and 124 being hoisted up. The dog 152 is first lifted, and the crank turned to rotate the gear-wheel 148 so as to unwind the chain on the windlass, whereby the wheels and axle are lowered. Continued 40 operation of the crank then produces fur-

ther winding of the chains on both ends of the windlass, so as to lift the machine bodily, and when this has been accomplished, the detent 152 engages the notch 151 in the drum, and the parts are automatically locked. Continued rotation of the crank shaft will now result in rotating the pinion, 144, and the crank-shaft 145, in planetary fashion around the gear-wheel 148, and as the road wheel 124 is fixed to the pinion 70 bearings, it is turned also, and with it the axle 121 and the wheel 122. Thus the machine may be expeditiously rolled at right angles to the track to remove it from the path of an oncoming car. To replace the 75 machine, the crank motion is first reversed so as to reverse the planetary gear effect, and turn the wheels, 122 and 124, in reverse direction to again bring the machine over the track rails. The dog 152 is then lifted, 80 and the crank 135 slowly rotated backward to continuously keep the clutch parts 148, 149 sufficiently uncoupled to permit the windlass to turn slowly and lower the machine on the track. In so doing, the crank 85 cannot fly around, nor the machine be dropped suddenly, as any stoppage in the reverse motion of the crank will result in locking the screw parts 156. A chock 122^c (see Fig. 2^c) may be conveniently attached 90 to the rim of one of the road-wheels, as 122, by means of the hooked bolts 122^b. This chock serves as a reactive means to prevent rolling of the road wheels when the weight of the machine is being hoisted thereon, 95 and it also serves to accurately and expeditiously locate the machine over the rails after the same has been rolled aside to permit the passage of a car. Inasmuch as the road-wheels in practice make but half a 100 revolution to clear the car, the chock may remain on the road-wheel except when machine is being transported over a distance greater than its circumference.

Connected to the sleeve 132 by a hand-wheel friction clutch 160, is a winding drum 161. The purpose of this drum is to wind up a cord 162 attached to the trolley pole of the machine so as to draw down the pole automatically when the machine is being 105 hoisted on the axle to permit an approaching car to pass. The trolley pole rigging is shown in Fig. 4, the cord 162 extending to a suitable sleeve 163 on the pole 164, which has at one end a fork 165 (or trolley wheel) 110 to engage the trolley wire, and is secured near the other end in a sleeve 166 pivoted at 167 to the post 168. Outside of the sleeve a cap 169 is fitted to the end of the pole and carries a T-head 170 with its ends projecting transversely to the pole, and each of them receiving a hook 171 on the end of one of a pair of springs 172, the other ends of which are secured to the opposite ends 115 of a sliding cross head 173 secured by means 120 of a sliding cross head 173 secured by means 125 of a sliding cross head 173 secured by means 130

of a set screw or similar device 174 on the diagonal brace 175 which is secured at its lower end in a cast iron socket 176 on the machine bridge 120 and carries at its other end a bearing sleeve 177 in which the post 168 can turn. The foot of the post is received and journaled in a cast iron socket 178 secured on the bridge member 120 of the machine. Around the outside of the socket is fitted a loose collar 179, secured to the post 168 by a pin fitting the collar and post tightly but working in horizontal slots in the walls of the socket 178, as shown in Fig. 4^a. Above the collar 179 stop collar 180 is pinned on the socket 178 permanently. Thus, by taking out the pin 181, the post 168 and its rigging can be removed while the collar 179 will remain on the machine. This collar has ears 182 which receive a handle lever 183 between them, this lever being pivoted for vertical oscillation, and connected by means of a chain 184 to the detent 152 (Figs. 2^a and 3^b). The lateral play of the pin 181 in its slot, enables the operator to turn the post 168 and the pole 164 from side to side by means of the lever 183, this motion being necessary when the pole 164 is being elevated, in order to engage the fork 165 with the trolley wire. By raising the handle 183 the operator can lift the detent, and release the drum, one hand serving to perform both operations of guiding and releasing, leaving the other hand free to manipulate the crank or perform other necessary acts in setting or resetting the machine for operation. The fitting 177 may be provided with eyes on its sides to receive the ends of lateral head guys 185, the lower ends of which are secured to eyebolts on the frame members 1 and 2. By this arrangement a very light rigging can be employed, the post 168 being for example a 2 inch steel boiler tube, the strut 175 being of 1½ inch tubing, and the head guys being standard $\frac{3}{16}$ inch galvanized iron. The post 168 being tubular, the supply conductor can be led down inside it, being shown at 186 led out of the post to the pole. Slack enough must be provided in this connection to permit turning of the pole on the pivot 167 through its maximum angle of movement. When the pole is all the way down, it lies along or substantially parallel with the strut 175. The pole 164 is shown as of wood but may obviously be made of metal if desired. One of the pair of springs 172 may also be omitted. The remaining spring may be housed inside the strut 175, in which case short pieces of rope would connect the top end of the spring with the trolley pole, and from the bottom end of the spring a rope would pass out at the bottom end of the strut to haul and hold the fork against the trolley wire.

There are some features in this machine

which should be specially noted. The provision of rigid connecting means in the form of posts 7—8, and their braces, makes it possible to suspend the entire machine from the road wheels in stable equilibrium, without oscillation, except in an arc of long radius. The provision of the transverse road wheels and the various adjustments I have provided, makes it possible to stop the machine, run it off the track transversely to permit the passage of a car, run it back again, lower it on the track, and continue the grinding without change or loss of adjustment, from the exact point at which it was stopped. So far as I know, this cannot be done with any other machine in existence. Moreover, this machine is self-contained, that is to say, it is a single unit, containing both the driving supports or wheels and the grinding supports or travelers, the feeding means and the propelling means all within itself. So far as I know this combination is not found in any other machine in existence. It is a small power machine, and it will be obvious to those skilled in the art that by introducing a simple train of gears from the power shaft 13 to the gear wheel 148, with a proper reversing clutch connection, the machine may be hoisted and taken off the track or replaced by power from the motor instead of the crank 135. In this case the trolley connection must remain established and be laterally flexible.

Brief and temporary removal from and replacement on the track, the displacement of the machine being only a few feet in either direction, can be accomplished with the chain suspension, without excessive vibration, but the arrangements referred to lend themselves very well to spring suspension for transportation from place to place, where the unyielding chain suspension would transmit every vibration due to inequalities in the road bed, with injurious effect to the machine. The simplest form of spring suspension is that in which the lower end of each chain 136 or 140 has a hook which can be engaged with an eyebolt on the frame member 3 or 4, and in addition to the heavy coiled spring or spring boxes, is secured to the frame with an eye or hook to engage the chain. By unhooking the end of the chain from the eyebolt on the frame, and engaging the chain hook or one of its links with the eye or hook on the spring, the suspension may be made resilient for distance transportation; while it is only necessary to unhook the chain from the spring and reengage its terminal hook with the eyebolt on the frame, to restore a rigid lifting connection for use during grinding as hereinbefore described. While this insertion of a spring in the chains is the simplest and most obvious arrangement, I do not consider it the best for my purpose, but for

purposes of distance transportation, I preferably provide the spring boxes 186 (shown in dotted lines in Fig. 3), of which one box is shown in section in Fig. 5. The specific form and arrangement of this spring box is not material, so long as it will subserve the function for which it is intended, and which is material and essential. This function is to cushion the suspension of the machine from the wheels 122 and 124 by suitable means interposed between the axle boxes 131, 131^a, and the upper ends of the vertical suspension frame 7—7^a, 8—8^a, 120. Suppose the machine has been hoisted, so that the vertical frame pieces 7—7^a, 8—8^a have risen, with respect to the axle boxes 131, 131^a, obviously the space in each vertical slot between the axle box and the head or bridge member 120 will be much higher than normal. Into these spaces the boxes 186 are inserted, one on each side, and in order to prevent lateral displacement of the boxes under strain, suitable holding means may be provided therefor, in the shape of flanges or projections, either on the spring boxes or the axle boxes, or on the frame. The detent 152 may then be disengaged from the slot in the drum 149, and a few backward turns of the crank handle will impose the entire weight of the machine on the springs in the boxes 186, and the general arrangement will at once become quite similar to that of the frames and journal boxes on a railway truck. A great advantage gained by this arrangement is that the line of support for the entire weight of the machine is at its highest part, that is along the bridge member 120. This tends to lessen oscillation.

Means for transporting the machine are shown in Fig. 6, the arrangement being such that while the tractile force is applied directly to the axle 121, the frame of the machine is held to prevent excessive oscillation, and receives its due portion of the impetus due to the propelling force. Two draw bars 187, 188 are provided which may conveniently be steel tubes with solid ends welded to them, these ends being flattened and provided with bolt holes. The end 187^a is bolted between the projecting ears on a collar 187^b encircling the axle, and the end 188^a is similarly bolted between ears on a collar 188^b. The ends 187^c and 188^c are secured by a throughbolt with the head of a draw bar adjuster or link 189 between them. The lower end of this link is provided with a number of bolt holes by which it can be adjustably secured between a pair of ears on the frame member 3 or 4. The ends 187^c and 188^c project and are provided with bolt holes for the attachment of a link or other means for connecting the draw bars to the rear end of a wagon or truck or to a swingletree for direct hauling. Thus, with

the spring suspension and steadyng link, the machine may be transported any distance with ease and security.

I am aware that many changes and modifications may be made in this machine without departing from the scope or purview of the invention. It is to be clearly understood that I contemplate all such non-essential changes and modifications as fairly fall within the terms of the appended claims.

Having thus described my invention what I claim and desire to secure by Letters Patent is—

1. In a rail grinder adapted to operate upon either rail, a truck for the grinder mechanism comprising a platform; a traction wheel; a power shaft mounted upon said platform; means operated thereby adapted to rotate said traction wheel in two directions; and means extending upon opposite sides of said platform adapted for selecting the direction of rotation imparted to said traction wheel, said means being adapted to be conveniently operated by operators at either side of said platform.

2. In a propulsion mechanism for trucks, the combination comprising a platform, a traction wheel; an axle fixed to said wheel; a pair of drive gears freely rotatable upon said axle; means for rotating said drive gears in opposite directions; a pair of clutch members one fixed to and rotatable with each of said gears; a shiftable clutch member feathered upon said axle adapted to be shifted for engagement with either of said first mentioned clutch members whereby the movement of such clutch member thus engaged may be transmitted through said shiftable clutch member to said axle for rotating said axle and said traction wheel in the direction of rotation of the drive gear to which the engaged clutch member is fixed; and means extending upon opposite sides of said platform whereby said shiftable clutch member may be conveniently shifted at will by operators at either side of said platform.

3. In a propulsion mechanism for trucks; the combination comprising a platform; a traction wheel; an axle fixed to said wheel; a pair of drive gears freely rotatable upon said axle; a pair of clutch members one fixed to and rotatable with each of said gears; a shiftable clutch member feathered upon said axle adapted to be shifted for engagement with either of said first mentioned clutch members; a power shaft mounted upon said platform; supplemental power shafts driven by said first power shaft and adapted to drive said drive gears in opposite directions; and means extending upon opposite sides of said platform whereby said shiftable clutch members may be conveniently shifted at will by operators at either side of said platform.

4. In combination a truck frame, and pro-

5 propelling mechanism therefor comprising propelling wheels, a source of power, a driving connection from the source to the propelling wheels, and automatic means on the frame for reversing the latter drive after a predetermined travel of the machine in either direction.

10 5. In combination a truck frame, and propelling mechanism therefor comprising propelling wheels, a motor on the frame, power transmission means connecting said motor with the propelling wheels, a clutch determining the continuity and direction of said power transmission, and a timing element on the frame controlling said clutch.

15 6. In combination a truck frame, and propelling mechanism therefor comprising propelling wheels, means to supply power to the axle of the propelling wheels, a reversible coupling determining the continuity and direction of the application of power to the propelling wheels, a timing element on the frame, and operating means for said coupling controlled by the timing element.

20 7. In combination a truck frame and wheels, a source of power carried by said frame, and reversible power transmitting connections between said motor and said wheels controllable from points laterally on each side of said truck frame whereby the truck may be controlled in its forward and reverse movements from either side of the track-way at will.

25 8. A machine of the character described comprising a main truck frame and wheels, auxiliary derailing wheels, supporting connections between the auxiliary wheels and the main truck frame whereby the main truck frame may be supported free from the ground by said auxiliary wheels, and manually operable power applying means including power multiplying wheels geared to said derailing wheels whereby the power may be manually applied to said derailing wheels independently of the main truck frame to roll the machine from the trackway.

30 9. In a machine of the character described, a main truck frame provided with vertically extended guideways arranged longitudinally of the main body and above its center of gravity, a supporting wheel journaled in each of said guideways, and a hoisting mechanism between said main truck frame and the said auxiliary wheels.

35 10. A machine of the character described comprising a main truck frame and wheels, provided with vertically extended guideways above the center of gravity of said main body, an auxiliary supporting truck connected with said main truck frame through said guideways, and a hoisting mechanism between said two trucks whereby the main truck may be hoisted upon said auxiliary truck and transported from the trackway.

40 11. A machine of the character described comprising a main truck frame and wheels, a longitudinally extending axle overlying said truck and extending substantially across its main body, a pair of auxiliary wheels one at each end of said axle and a hoisting device adapted to raise said machine from a trackway and support it from said axle.

45 12. In a machine of the character described, a main truck, auxiliary wheels adapted to support said main frame for transportation from a trackway, hoisting connections between the main body and the said auxiliary wheels for raising the main truck upon the auxiliary wheels, and a differential gearing between one of said auxiliary wheels and the said hoisting connection.

50 13. A machine of the character described comprising a main truck, an overlying axle carrying auxiliary wheels and from which the main truck frame may be supported for transportation, hoisting connections between said axle and said main truck frame, and a differential gearing between one of the auxiliary wheels and the said axle, and means for applying power to said differential gearing to operate both the axle and the wheels, the one to hoist the main truck onto the wheels, and the other to revolve the wheels to transport the main truck from the trackway.

55 14. In a machine of the character described a main truck, auxiliary wheels on opposite sides of said main truck and on which said main truck is adapted to be transported from a trackway, and a clutch device for connecting and disconnecting said wheels whereby they may be caused to move in synchronism or asynchronism to guide the movements of the main truck during transportation.

60 15. A machine of the character described comprising a main truck frame and wheels, auxiliary wheels on opposite sides of said main truck frame on which said main truck frame is adapted to be transported from the trackway, a power device for applying power to said auxiliary wheels to effect transportation, and a clutch device connecting said auxiliary wheels operable from a point closely adjacent to said power device, whereby a single operator may simultaneously operate both the clutch device and the power applying means.

65 16. In a machine of the character described a main truck frame and wheels, auxiliary derailing wheels, and means for hoisting the main truck upon auxiliary wheels comprising a power multiplying gearing having an adjustable ratio of transmission.

70 17. In a machine of the character described a main truck frame and wheels, auxiliary derailing wheels, and means for hoisting the main truck upon auxiliary wheels

- comprising a power multiplying gearing and a crank for turning the same which crank has an adjustable throw whereby the ratio of transmission of the gearing may be altered at will.
18. A machine of the character described comprising a main truck frame and wheels, auxiliary derailing wheels associated therewith, a hoisting means between said auxiliary wheels and the main truck, and a manually operable differential gearing between the hoisting means and one of the auxiliary wheels, together with means for stopping the operation of the hoisting mechanism through the differential at a predetermined point whereby the main truck is held suspended in raised position, and whereby further operation of the differential operates the auxiliary wheels to move the machine from the trackway.
19. A machine of the character described comprising a main truck frame and wheels, auxiliary derailing wheels, hoisting connections between the main truck and the auxiliary wheels, and a differential operating gearing between one of said auxiliary wheels and said hoisting connections together with means for automatically stopping rotation of that one of said auxiliary wheels at a predetermined point, whereby continued operation of the differential will lower the main truck frame from the auxiliary wheels.
20. A machine of the character described comprising a main truck frame and wheels, auxiliary derailing wheels, hoisting connections between the main truck and the auxiliary wheels, and a differential operating gearing between one of said auxiliary wheels and said hoisting means together with means for automatically stopping the rotation of that one of said auxiliary wheels at a predetermined point, whereby continued operation of the differential will lower the main truck frame from the auxiliary wheels, and additional hoisting connections between said main frame and said auxiliary wheels, whereby further continued operation will thereafter raise the auxiliary wheels from the ground and hold them suspended from the main truck.
21. A machine of the character described comprising a main truck frame and wheels, auxiliary wheels, hoisting connections between said auxiliary wheels and said main frame, by which said main truck may be hoisted upon said auxiliary wheels, means for locking and holding said main truck frame in hoisted position on said auxiliary wheels, a power multiplying gearing associated with said hoisting connections and manually operable means unlocking said holding means at will, together with a brake device which prevents the immediate dropping of said main truck upon its release.
22. A machine of the character described comprising a main truck frame and wheels, auxiliary wheels, hoisting connections between said auxiliary wheels and said main body by which said main truck may be hoisted upon said auxiliary wheels, means for locking and holding said main truck frame in hoisted position on said auxiliary wheels, a power multiplying gearing associated with said hoisting connections and manually operable means unlocking said holding means at will, together with a brake device which prevents the immediate dropping of said main truck frame, and a let-off device for the brake.
23. A machine of the character described comprising a main truck frame and wheels, auxiliary wheels, hoisting connections between the auxiliary wheels and the main truck frame, and a differential gearing between the hoisting connections and said main truck frame operable in one direction to raise the main truck upon the auxiliary wheels, and in the other direction to lower the main truck frame and thereafter hoist the auxiliary wheels thereon, and locking means operable in the first case to lock the main truck frame in raised position and in the second case to lock the auxiliary wheels in raised position, together with manually operable means for releasing said lock at will.
24. A machine of the character described comprising a main truck frame and wheels, auxiliary derailing wheels, and hoisting connections between the auxiliary wheels and the main truck frame comprising a rotatable member and hoisting chains connected with said main truck frame both above and below said member.
25. A machine of the character described comprising a main truck frame and wheels, an overlying hollow shaft, an axle journaled in said shaft and provided on each end with an auxiliary wheel, a hoisting connection from each end of said hollow shaft to the main truck frame, and means for rotating said hollow shaft independently of the axle and auxiliary wheels to hoist said main truck frame upon and support it from said auxiliary wheels.
26. A machine of the character described comprising a main truck frame and wheels, auxiliary wheels, hoisting connections between said auxiliary wheels and said main truck, means for locking the main truck frame in raised position, a trolley pole connected with said main truck frame, and a controlling member connected commonly to said locking means and to said trolley pole and operable simultaneously to release said lock and to adjust said trolley pole.
27. A machine of the character described comprising a main truck frame and wheels, auxiliary derailing wheels, a hoisting mechanism between the said auxiliary wheels and the main truck frame whereby the main

truck frame may be raised upon said auxiliary wheels and lowered therefrom, a trolley supported from said main truck frame, and connections between said hoisting mechanism and said trolley adapted to remove and replace the trolley from operating position when the hoisting mechanism is operated.

28. A machine of the character described comprising a main truck frame and wheels, auxiliary derailing wheels, a hoisting mechanism between the said auxiliary wheels and the main truck frame whereby the main truck frame may be raised upon said auxiliary wheels and lowered therefrom, a trolley supported from said main truck frame, and connections between said hoisting mechanism and said trolley adapted to remove and replace the trolley from operating position when the hoisting mechanism is operated, and means for adjusting the ratio of said connection to define the extreme positions of said trolley.

29. In a machine of the character described, a main truck frame and wheels, a self-contained derailing truck permanently connected with said main truck frame, means for lifting the main truck frame and supporting it upon said derailing truck, and a draft yoke connected with said derailing truck.

30. A machine of the character described comprising a main truck frame and wheels, a derailing truck comprising a single over-lying axle with a wheel on each end over-lying said main truck frame and permanently connected thereto for vertical movement with respect thereto, and a draft yoke connected with said axle.

31. In a machine of the character described, a main truck frame and wheels, a derailing truck permanently connected therewith for vertical movement with respect thereto, means for hoisting said main truck frame upon and suspending it from said derailing truck, a draft yoke connected with said derailing truck, and a connection between said draft yoke and one end of said main truck frame whereby the main truck frame is steadied during transportation with the draft connection by said yoke.

32. In a self-contained mobile rail grinding machine in combination a truck frame, supporting means for the frame adapted to travel on the rail, and independent supporting means for the frame adapted to travel off the rail, with means for lifting the machine on the second supporting means with the first supporting means clear of the rail, an additional means for lifting the second supporting means on the machine to permit free travel of the first supporting means along the rail, and means for applying power independently to either of said supporting means to produce travel of the machine on or off the rail at will.

33. In a self-contained mobile rail grinding machine in combination a truck frame, a track wheel and road wheels, a lifting device adapted to support the weight of the machine on the road wheels with the track wheel clear of the rail, and means to apply power independently to the track wheel or a road wheel to produce travel of the machine along the rail or independently of the rail at will.

34. In a self-contained mobile machine for dressing metal parts such as railway rails when in fixed position in combination a frame, a support for the frame adapted to travel on the metal or rail operated upon, a separate support adapted to travel independently of the metal or rail, hoisting mechanism adapted to lift the weight of the machine on said second support, means for applying power to said hoisting mechanism arranged also to automatically apply power to said second supporting means for moving the machine independently of the metal or rail.

35. In a self-contained mobile rail grinding machine in combination a frame, supporting means adapted to travel on the rail, and a pair of road wheels, a hoisting connection from said road wheels to the frame, gearing attached to said wheels and operatively connected to the hoist, means to apply power thereto for operating the hoist while said wheels remain stationary, and means to lock the hoist whereby continued application of power will turn the wheels.

36. In a self-contained mobile rail grinding machine in combination a frame, supporting means adapted to travel on the rail, and a pair of road wheels, a hoisting connection from said road wheels to the frame, sliding bearings on the frame for said road wheels, a gear journaled in bearings fixed to the road wheels and means to apply power thereto, an intermeshing gear fixed to the hoist, said gears and road wheels being in fixed relation to said sliding bearings, and means to lock said hoisting gear, whereby rotation of the first gear will operate the hoist when not locked while said road wheels remain stationary, but will turn the wheels in their bearings when the hoist is locked.

37. In a self-contained mobile rail grinding machine in combination a frame, supporting means adapted to travel on the rail, and a pair of road wheels, a hoisting connection from said road wheel to the frame, a pair of vertical supports on the frame, a bracket carried above the frame on said supports, sliding journal boxes traveling vertically in said supports, a tubular windlass journaled in said bearings, a pair of road wheels outside the supports, an axle passing through and journaled in said windlass and rigidly secured to the hubs of said road wheels, a flexible suspender secured at

its upper end to said bracket and at its lower end to the frame and intermediate of its ends engaged by said windlass, a gear wheel coupled to said windlass concentrically, a pinion intermeshing therewith and journaled in bearings carried by and eccentric to one of the road wheels, means for applying power to said pinion, and a detent for locking said windlass and its gear wheel 5 with respect to the frame, whereby rotation of the power driven pinion in one direction will rotate the windlass to draw up the suspender and lift the frame until the detent is locked, and thereafter continued rotation 10 of said pinion will cause it to travel around the windlass gear with a planetary motion and to turn both road wheels and their axle for propelling the machine on said road wheels; and rotation of said pinion in reverse direction will reverse the motion of the road wheels while the detent remains locked and thereafter while said wheel remains stationary will reverse the motion of the windlass to unwind the suspender and 20 to lower the frame of the machine until it rests on the rail and finally will reversely wind the suspender and lift the windlass, the axle, the road wheels, and their journal boxes and gears to suspend the same on the 25 frame of the machine, said suspension being maintained by again locking the detent to prevent rotation of the windlass:

38. In a mobile rail dressing machine adapted in operation to rest upon the rail 35 being dressed, a pair of rigid supports projecting vertically from said machine on a median line across its mass, a pair of wheels with an axle therefor extending across said supports parallel to and above said median 40 line and above the center of gravity of the machine, with means to lift the machine and, when lifted, to secure said supports to the axle in suspension.

39. In a mobile rail dressing machine, the 45 combination of traveling supporting means for moving the machine to and from the rail, an electric motor for operating the machine, a contact device adapted during operation to occupy an extended position in contact 50 with a supply conductor, such as a trolley wire, a hoisting device for imposing the weight of the machine on the traveling supporting means, and a retracting device for said contact adapted to be automatically actuated in the operation of the hoist.

40. In a machine of the character described, a main truck frame on wheels, auxiliary wheels adapted to support said main truck frame free from the ground independently of said main wheels, a differential 60 hoisting gearing having one element connected to said auxiliary wheels and another

element connected to said main truck frame, with a third element adapted to supply power to either of the first two elements 65 when the other is held stationary, whereby when one of the auxiliary wheels is held stationary, the main truck frame may be hoisted upon said auxiliary wheels, together with means to stop the rotation of said auxiliary wheels and the transportation of said main truck frame thereon when the auxiliary wheels have rotated a predetermined distance, whereby the auxiliary wheels being held stationary, the truck frame may be 70 raised or lowered.

41. In a machine of the character described, a main truck frame on wheels, auxiliary wheels adapted to support said main truck frame free from the ground independently of said main wheels, a differential hoisting gearing between said auxiliary wheels and said main truck frame whereby when one of the auxiliary wheels is held stationary, the main truck frame may be 80 hoisted upon said auxiliary wheels, together with a chock extending beyond the periphery of one of said auxiliary wheels and removable at will from the periphery of the wheel.

42. A machine of the character described comprising a main truck frame and wheels, auxiliary transporting wheels permanently associated therewith and on which the main truck frame may be supported for transportation, said auxiliary wheels being of a diameter such that one revolution or less is sufficient to transport the main truck frame from the danger zone of a trackway, a chock associated with one of said auxiliary wheels and active once each revolution to stop transportation, together with a differential hoisting gearing between said auxiliary wheels and said main truck frame, whereby when the auxiliary wheel is stopped 90 the main truck frame is moved through the differential gearing with respect thereto.

43. In a machine of the character described, a main truck frame and wheels, a horizontal shaft permanently associated 100 with said main truck frame together with auxiliary wheels connected therewith, a hoisting connection between said auxiliary wheels and main truck frame, and means for rotating the said shaft independently of 110 the auxiliary wheels to hoist the main truck frame and support it on the auxiliary wheels 115 from the ground.

In testimony whereof I affix my signature in presence of two witnesses.

WILLIAM D. GHERKY.
